UNITED STATES PATENT OFFICE

LOREN P. MICHAEL, OF ELMHURST, ILLINOIS, ASSIGNOR OF ONE-HALF TO THE BALDWIN LOCOMOTIVE WORKS, OF PHILADELPHIA, PENNSYLVANIA, A CORPORATION OF PENNSYLVANIA

LOCOMOTIVE CONSTRUCTION

Application filed May 3, 1929. Serial No. 360,193.

My invention relates to railway rolling stock and particularly to the construction of cylinder and boiler saddle structure of a locomotive and the combination therewith of a smoke-box mounted on the saddle and a feed water heater contained in the smoke-box.

It is customary to provide pipes leading from the steam valve chambers and mounted on the outside of the smoke-box and extending through the wall of the latter to a feed water heater carried in the upper portion of the smoke-box.

The main object of my invention is to eliminate a substantial part of this piping and to simplify the construction and reduce the labor of assembling the piping and other structure and also to reduce the likelihood of undesirable leakage of air into the smoke-box due to the presence of joints where the piping would ordinarily extend through the smoke-box wall. I attain this object by providing an exhaust steam passage, in addition to the main exhaust steam passage, in the saddle structure itself and having a discharge opening in the web plate of the saddle which supports the boiler, this opening leading to the interior of the smoke-box.

Other more detailed objects of my invention and the means for attaining the same will be apparent from the detailed description of my invention and from the accompanying drawings in which—

Figure 1 is in part a top view and in part a horizontal section taken on the line 1—1 of Figure 2.

Figure 2 is a vertical transverse section taken on the line 2—2 of Figure 1.

Figure 3 is a side elevation of the saddle and feed water heater members, the adjacent portion of the smoke-box being shown in broken lines.

Figure 4 is a vertical longitudinal section taken on the line 4—4 of Figure 1.

Figure 5 is a vertical transverse section taken on the line 5—5 of Figure 3.

Figure 6 is a vertical longitudinal section taken on the line 6—6 of Figure 1.

Figure 7 is a detail horizontal section taken on the line 7—7 of Figure 2.

Preferably, although not necessarily, my

saddle structure is formed in one piece and is integral with the locomotive bed or forward framing members 1. I illustrate a portion of the bed of box-shaped cross section and having the steam cylinders 2 and the steam valve chambers 3 formed integrally therewith. The cylinders and valve chambers on opposite sides of the bed are connected by suitable transverse walls 4 which extend upwardly beyond the level of the valve chambers and carry the web plate 5 which forms the boiler support member of the saddle. The boiler smoke-box is indicated at 6 and is mounted upon web plate 5 and is secured thereto in the usual manner.

Integral with the saddle structure are the main exhaust steam passages 7—7 which lead from the ends of each steam chamber 3 transversely and longitudinally and upwardly of the saddle through the center of the web plate 5 where they form a seat 8 upon which an exhaust nozzle (not shown) may be mounted.

I provide additional or by-pass exhaust steam passages 9 leading from the main exhaust steam passages 7 at a point abreast of the front end of the steam chamber and extending transversely and upwardly of the saddle and through the web plate 5 near the front of the latter and the outside flange 80 of the web plate is projected forwardly as indicated at 10 to accommodate the upper end of passage-way 9. This passage-way 9 terminates in a flanged portion 11 having a seat 12 for mounting a pipe 13 which is curved 85 concentrically with the boiler shell and leads to a feed water heater 14 carried in the upper portion of the shell.

The steam passages 9 on opposite sides of the saddle preferably have a common discharge outlet 15 and only a single pipe and pipe connection is required for the feed water heater steam line and this connection is located on the inside of the smoke-box, thus eliminating any joints in the wall of the latter through which cold air can be drawn or which require inspection at intervals in order to maintain the same in tight condition.

In order to direct the steam stream from 100

the valve chambers 3 through the main exhaust passage-way 7, I provide a projection 19 at the junction between passages 7 and 9 and this eliminates undesirable back pressure in the main exhaust passage-way 7 which would be present if this projection were not provided or if some other corresponding device were not used.

I also desire to simplify the complete locomotive structure by forming a bracket 16 integrally with the saddle for the purpose of mounting a combined steam cylinder and reciprocating water pump 17. This bracket projects outwardly from the upper wall 18 of the saddle structure which extends between the right-hand steam chamber 3 and the corresponding side of the boiler supporting web plate 5.

It will be understood that the location and formation of the elements of my novel saddle structure may be varied from that shown without departing from the spirit of my invention. The feed water heater steam passages may extend along the rear wall of the saddle instead of along the front wall and may lead to different outlet or discharge points than those shown, and the pump bracket may be located immediately over the steam supply chamber or at any intermediate point on wall 18. The feed water heater steam passages could readily be located in a cylinder saddle of the type in which the cylinders are formed separately and bolted to the cylinder mounting elements of the saddle and my invention also contemplates the use of a saddle split along the longitudinal center line of the locomotive in accordance with the well-known practice in this art. As previously stated, the saddle in any of the forms referred to may be made integral with or separate from the framing members of the locomotive. I contemplate the exclusive use of these and other modifications of my invention which come within the scope of my claims.

I claim:

1. In a locomotive cylinder saddle, a front wall, and an exhaust steam passage-way extending along said wall and having a side formed by said wall.
2. In a locomotive cylinder saddle, a front wall, and a plurality of exhaust steam passage-ways extending along said wall from opposite sides of the saddle towards the longitudinal center line thereof and each having a side formed by said wall, said passage-ways leading upwardly through the top of the saddle and terminating in a common outlet.
3. In a locomotive cylinder and boiler saddle structure, a mounting for an exhaust nozzle, a passage-way in the said saddle structure for exhaust steam leading to said mounting, and another passage-way in the said saddle structure for exhaust steam leading to a point spaced from said mounting.
4. In a device of the class described, a

steam cylinder supporting element, a boiler smoke box supporting member, a passage-way for exhaust steam leading from a point adjacent to said element through an outlet on said member, and another passage-way for exhaust steam leading from a point adjacent to said element and through said member at a point spaced from said outlet.

5. In a locomotive cylinder and boiler saddle structure, a mounting for an exhaust nozzle, a mounting for a steam pipe for a feed water heater, said mountings being spaced apart, and individual passage-ways for exhaust steam in said saddle structure leading to said mountings.

6. In a locomotive device, a steam supply chamber, a boiler supporting member, an exhaust nozzle mounting, a feed water heater pipe mounting, an exhaust steam passage-way leading from a point near the end of said chamber to said nozzle mounting, and an exhaust steam passage-way leading from a point near the end of said chamber to said pipe mounting, all of said elements being integral with each other.

7. An integral structure for locomotives comprising spaced steam supply chambers, a member connecting said chambers, and including a boiler support, main exhaust steam passages leading from points near the ends of said chambers to the top face of said support near the center thereof, and exhaust steam passages leading from points near the ends of said chambers to a common opening in the top face of said boiler support near the end thereof.

8. In a locomotive saddle for steam cylinders and boiler, an exhaust steam passage extending diagonally inwardly of the saddle from the outside end of the structure, and a passage in the saddle leading from the outer end of said first mentioned passage transversely of the saddle for conveying steam to a feed water heater.

9. In a locomotive, a cylinder and boiler saddle, a steam valve chamber at the side of said saddle, a boiler smoke-box carried on said saddle, a feed water heater in said smoke-box, and an exhaust steam conduit within said saddle and smoke-box and leading from said valve chamber to said heater.

10. In combination, a steam cylinder, a valve chamber, a main exhaust steam passage, a top web plate, and a feed water heater exhaust steam passage connected to said main exhaust steam passage and extending through said web plate.

11. In an integral cylinder saddle structure, a steam cylinder, a valve chamber, a main exhaust steam passage, a top web plate, and a feed water heater exhaust steam passage connected to said main exhaust passage and extending through said web plate.

12. In a cylinder saddle structure, a pair of steam cylinders, a steam valve chamber

- above each of said cylinders, a top web plate, a main exhaust steam passage extending inwardly from each of said valve chambers and having a discharge opening in said web plate, 5 and a feed water heater exhaust steam passage connected to each of said main exhaust passages and having a discharge opening extending through said web plate and spacer from said first mentioned opening.
13. In an integral cylinder saddle structure, a steam cylinder, a valve chamber, a top web plate, a main exhaust steam passage extending from said valve chamber through said web plate, a feed water heater exhaust steam passage connected to said main steam passage and extending through said web plate, and a flange on the end of said feed water heater exhaust steam passage spaced from said web plate for mounting a feed 20 water steam pipe.
14. In a cylinder saddle structure, a cylinder, a valve chamber, a top web plate, a main exhaust steam passage extending transversely and rearwardly from the front end portion 25 of said valve chamber and upwardly to an opening in the central portion of said web plate, and a feed water heater exhaust steam passage connected to said main steam passage and extending inwardly in line with the 30 transverse portion of said main steam passage and also extending upwardly and through said top web plate.
15. In a cylinder saddle structure, a steam cylinder, a steam valve chamber, a top web 35 plate, a main exhaust steam passage extending transversely and rearwardly and upwardly from the front end portion of said valve chamber to an opening in the central portion of said web plate, a feed water heater exhaust steam passage connected to said main 40 exhaust passage and extending transversely and upwardly through said web plate, and a curved projection on the inside of said exhaust passages at the junction thereof to direct the steam stream into said first mentioned passage.
16. In an integral locomotive bed structure, steam cylinders, valve chambers, a smoke-box support having a top web plate, 50 main exhaust steam passages leading from the end portions of said valve chambers to the central part of said web plate, and feed water heater exhaust steam passages connected to the front branches of said main exhaust steam 55 passages and extending upwardly therefrom through said web plate.
17. A locomotive cylinder saddle having an integral bracket projecting from the saddle body and adapted to mount a feed water pump.
18. In a locomotive boiler and cylinder saddle, a boiler supporting web, a steam valve chamber, a wall connecting said web and chamber, and a bracket formed on said wall and adapted to mount a feed water pump between said web and chamber.
19. In a locomotive cylinder saddle, a front wall, a rear wall, and a feed water heater exhaust steam passage-way extending along one of said walls and integral therewith.
20. In a device of the class described, a boiler support member, a steam chamber, and an exhaust steam passage-way leading from said chamber, said passage-way diverging into two branches extending through said member.
21. In a cylinder saddle structure, a pair of steam cylinders, a steam valve chamber above each cylinder, a top web plate, a main exhaust steam passage extending inwardly from each of said valve chambers and having a discharge opening in the center portion of said web plate, and a feed water heater exhaust steam passage having an inlet connected to each of said main exhaust passages and having a single discharge opening extending upwardly at the middle portion of said feed water heater exhaust steam passage through said web plate and spaced from said first mentioned opening.
22. In combination, a locomotive cylinder saddle, a main steam supply chamber, and a bracket integral with said saddle and projecting laterally therefrom to mount a water pump above said chamber.
23. In a locomotive boiler and cylinder saddle, a boiler supporting web, a steam valve chamber, a wall connecting said web and chamber, and a bracket formed on said wall and adapted to mount cylinders for steam and water which cylinders form a feed water pump located between said web and chamber.
24. The combination of a smoke-box of a locomotive, of a cylinder casting under the smoke-box, the cylinder casting having exhaust ports opening into the smoke-box, and a passage formed in the cylinder casting and forming a communication between an exhaust passage and a pipe within the smoke-box.
25. A cylinder structure for locomotives, having, in addition to the cylinders, valve chests, inlet and exhaust passages, an integral passage within the structure connected to an exhaust passage and opening into the smoke-box of the locomotive, and arranged to be coupled to a pipe leading to a feed water heater.
26. A locomotive steam cylinder casting assembly having exhaust ports and provided with a passageway leading from an exhaust port on each side of the locomotive and forming an exhaust steam take-off for feed water heater supply, said passageway joined in the form of a Y connection and terminating in an outlet at the top of the cylinder casting.
27. A locomotive steam cylinder casting assembly, having exhaust ports, and provided with a passageway leading from an exhaust port on each side of the locomotive and forming an exhaust steam take-off for feed water heater supply, the walls of said passageways

being formed integrally with the cylinder casting, said passageways joined in the form of a Y connection and terminating in an outlet at the top of the cylinder casting.

- 5 28. A locomotive steam cylinder casting assembly having exhaust ports and provided with a passageway connected with an exhaust port on each side of the locomotive at a point in close proximity to the valve assembly of
10 the cylinders of the locomotive, said passageways forming an exhaust steam takeoff for feed water heater supply and being joined at a point in proximity to the top of the cylinder casting, and a pipe for conducting exhaust steam connected to the joined terminals of
15 said takeoff passageways.

In testimony whereof I hereunto affix my signature this 22nd day of April, 1929.
